HAND LUGGAGE

George Henry Wheary, Racine, Wis., assignor to
 Wheary Trunk Company, Racine, Wis., a corporation of Wisconsin

Application May 11, 1934, Serial No. 725,065

12 Claims. (Cl. 190—41)

This invention relates to new and useful improvements in hand luggage, and has as an object to provide an inexpensive, light carrier capable of carrying garments neatly folded to preclude wrinkling.

More specifically it is an object of this invention to provide a hand luggage carrier in the form of an enclosing envelope composed of two complementary side members hingedly connected along one edge and provided with a continuous interlocking fastening means along its remaining edges, and having a garment supporting structure disposed therein to support the garments in neatly folded arrangement.

Another object of this invention is to provide a hand luggage carrier of the character described, wherein the garment supporting structure includes a supporting bar over which the garments to be carried are draped to hang at opposite sides of the supporting structure where they are held by the sides of the enclosing envelope, and in which handle means are provided to carry the luggage with the garment supporting bar uppermost.

Another object of this invention is to utilize the garment supporting member over which garments to be carried are draped, as a rigid backing or filler for the enclosing envelope which is preferably formed of leather, fabric or other similar flexible material.

Another object of this invention is to provide an inexpensive garment carrier and enclosing envelope therefor, which may be used to transport garments, or as a protection for garments hung away in a closet.

Another object of this invention is to provide a luggage case of the character described in which the garment supporting member has a drawer mounted therein in such a manner as to permit the same to be pulled out without disturbing the garments supported thereon.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiment of the invention constructed according to the best modes so far devised for the practical application of the principles thereof, and in which:

Figure 1 is a perspective view of a hand luggage carrier embodying this invention, and particularly designed to carry a man's suit, said view showing the carrier in its closed position;

Figure 2 is a perspective view of the carrier shown in Figure 1 in its open position;

Figure 3 is a perspective view of a ladies type luggage carrier in open position;

Figure 4 is a perspective view similar to Figure 1, but illustrating a slightly modified embodiment of the invention;

Figure 5 is a perspective view of the carrier shown in Figure 4 in open position and illustrating the manner in which a man's suit is packed therein;

Figure 6 is a detail perspective view illustrating the shirt pocket or receptacle of the carrier shown in Figures 4 and 5;

Figure 7 is a perspective view showing another modification of the invention;

Figure 8 is a detail section view taken through Figure 7 on the plane of the line 8—8;

Figure 9 is a view in elevation of a modified form of garment support; and

Figure 10 is a perspective view of the carrier shown in Figure 1, but with the garment support equipped with means to hold the lower ends of the garments in place.

Referring now more particularly to the accompanying drawings in which like numerals indicate like parts throughout the several views, and particularly to Figures 1 and 2, the numeral 5 designates the enclosing envelope of the carrier forming the subject matter of this invention and which consists of two side members 6 and 7 formed of a single length of leather, fabric, or any other suitable material, or consisting of two separate pieces connected along the bottom edge 8 of the envelope.

While the enclosing envelope is shown as formed of flexible material, it is readily apparent that a stiff leather, fiber board, or other rigid material may be employed. In such instances, the sides 6 and 7 would be connected by a hinge along the bottom edge of the envelope.

The side and top edges of the envelope are readily detachably connected by continuous interlocking fastening means 9, there being preferably two sets of such fastening means, each extending along one side edge and across half the top edge.

At a medial point, the side member 6 has a flap 10 at its top edge to fold down over the ends of the interlocking fastening means and be connected to the other side member 7 by means of

a snap fastener 11. Handles 12, secured to the side members 6 and 7, provide means for carrying the envelope.

Disposed within the envelope is a garment supporting member in the form of a flat stiff board 13. While not necessary, one edge of the board 13 is preferably hingedly connected by a flap 14 to the envelope adjacent its bottom edge 8 and the opposite edge of the board has an enlarged rounded molding 15 to provide a garment supporting bar over which the garments to be carried are draped.

A garment hanger 16 of conventional construction cooperates with the bar 15 to hold the garments in neat arrangement. The hanger is mounted opposite the bar to facilitate straightening the garments during packing. A T shaped head 17 detachably engaged with two upstanding lugs 18 fastened to the board adjacent its lower edge portion, serves to detachably mount the hanger.

In packing a man's suit, it is first properly placed on the hanger 16 which has been removed from the carrier. The hanger is then attached to the supporting board and with the board resting in a flat horizontal position, as shown in Figure 2, the suit is straightened and neatly arranged over the board 13 allowing the lower end thereof to hang down over the edge or bar 15. The board is then lifted to a raised position, shown in dotted lines in Figure 2, whereupon the suit drapes down over the opposite side of the board. Then, with the garment properly and neatly arranged on both sides of the board, the two sides 6 and 7 of the envelope are brought up over the sides of the garment and the interlocking fastening means closed.

In Figure 3, the adaptation of this invention to a ladies' garment carrier is illustrated. In its major elements, this embodiment of the invention is the same as that shown in Figures 1 and 2. An enclosing envelope of fabric, leather, or other similar material composed of sides 6' and 7' is provided, as well as a flat stiff garment supporting board 13'.

Aside from the difference in fittings necessitated by the adaptation of the carrier to ladies use, the distinction between the structure shown in Figure 3 and that of Figures 1 and 2, is that the side members 6' and 7' comprising the enclosing envelope are permanently connected along the upper edge of the envelope when the same is closed rather than along the bottom edge. The carrying handle, in this instance, is fastened to the closed edge portion 8', and the supporting board 13' is hingedly connected to the outer edge of the side member 7' as at 14'.

Being intended primarily to carry ladies' garments, the hanger structure is also different. The supporting board 13' has two projecting arms 19 adjacent its hinged connection 14' with the side member 7'. On these arms a plurality of hangers 20 are readily detachably mounted to be held in place by a retainer bar 21 having a releasable connection with the outer ends of the arms 19.

The manner of packing the garments in the carrier is deemed to be obvious from the disclosure, and is somewhat similar to that described in connection with Figures 1 and 2.

This embodiment of the invention also provides for the carrying of other articles of clothing, such as stockings and the like, and for this purpose, there is a pocket 22 formed on the inner surface of the side member 6', the pocket being

closed by a continuous interlocking fastening means 23.

Figures 4, 5 and 6 illustrate the type of carrier shown in Figure 3 arranged to carry a man's suit. In this embodiment of the invention, as in the ladies' carrier shown in Figure 3, the garment supporting board 13', which is identical in all respects to that shown in Figures 1 and 2, is hingedly connected as at 14' to the outer edge portion of the side member 7'. 10

The hanger supports 18' are long enough to accommodate a second hanger 16' which, to preclude the disposition of the shoulder portions of two suits directly above each other, has an elongated preferably flexible strap 24 connecting 15 its T shaped head 17' with the hanger proper.

The side member 6' of the enclosing member has a shirt pocket or receptacle 25, which is closed on three sides by a continuous interlocking fastening means 26. The three open sides 20 of the pocket preferably have flaps 27 to fold down over the articles placed therein, as shown in Figure 6, before the pocket is closed to afford added protection and preclude the possibility of having the garments catch in the interlocking 25 fastening means.

In Figures 7 and 8, the garment supporting board is made hollow to provide a chamber 27 for the reception of a shallow drawer 28, which pulls out from the side of the board as illustrated to permit access to the contents thereof without disturbing garments arranged on the supporting board. 30

The supporting board in each of the embodiments illustrated with the exception of that 35 shown in Figures 7 and 8, is a solid rectangular structure formed of wood or other suitable material either covered with cloth of neatly finished to afford an attractive appearance, and in each instance, the supporting board is large enough to 40 extend beyond the sides and beneath the lower ends of the garments draped thereover.

In all cases though, the supporting board is smaller than the side members comprising the envelope, so that the envelope extends beyond all 45 edges of the board. Consequently, the envelope is readily expandable in thickness to adjust itself to the contents of the carrier.

It is, of course, possible to skeletonize the board to further reduce the weight of the carrier and 50 in Figure 9, a board so formed is illustrated. Consequently, where the specification and claims refer to a supporting board or equivalent language is used, the term is not to be construed as limited to a rectangularly shaped board or even to 55 a board at all, as for the purposes of the invention, a frame-like metal structure could be used in place of a wooden board.

In each instance, the supporting board or member supports the garments in a neatly folded arrangement and the sides of the enclosing envelope serve to hold the garments against the opposite sides of the supporting board against derangement. 60

Also in each instance, the handles are so located that the garments, when the carrier is in its normal carrying position, hang down on opposite sides of the board draped over the supporting bar 15, which may be a separate molding as shown, or merely the edge of the board. 65

To hold the lower ends of the garments in place and facilitate closing the envelope, the supporting board may be provided with a flap 30 to fold down over the lower ends of the garments as shown in Figure 10. This flap is preferably 70 75

a piece of fabric secured to the hinged edge of the board and provided with a strap or cross bar 31 at the opposite edge, the ends of which are readily detachably connected with the board as 5 at 32.

From the foregoing description taken in connection with the accompanying drawings, it will be readily apparent to those skilled in the art to which this invention appertains, that this invention affords a convenient and exceptionally light 10 carrier for men's suits and ladies' dresses and other garments, and that while primarily intended for travelling use, it also provides a protecting envelope in which garments seldom used, may 15 be hung away and protected against dust and moths.

What I claim as my invention is:

1. Hand luggage comprising a rigid support having a garment supporting bar over which 20 garments to be carried may be draped to hang on opposite sides of said support, said support being of a size to extend beyond the sides and beneath the lower ends of garments draped over its garment supporting bar, a flexible enclosing 25 envelope for the support and the garments draped thereon devoid of any stiffening means other than said support and comprising two side members in the form of sheets of flexible material slightly larger than the support and connected along at least one edge, interlocking fastening means along the remaining edges of the side members to connect the same along said edges, and a handle for carrying the luggage with the garment supporting bar uppermost.

2. Hand luggage comprising, a flat stiff board, one edge of which provides a garment support over which garments to be carried may be draped to hang on opposite sides of the board, said board being of a size to extend beyond the sides and beneath the lower ends of the garments draped over its said edge, a flexible enclosing envelope for the board and the garments draped thereon comprising two side members in the form of sheets of flexible material slightly larger than the board and connected along at least one edge, closure means to connect the side members along their other edges, and a handle to carry the luggage with the garment supporting edge of the board uppermost.

3. Hand luggage comprising a flat stiff board one edge of which affords a garment support over which garments to be carried may be draped to hang on opposite sides of the board, a garment hanger over which the garments to be carried are folded preparatory to being draped over the board, means to mount said garment hanger at a point remote from the garment supporting edge of the board, said board being of a size to extend beyond the sides and beneath the lower ends of garments draped over its supporting edge, a flexible enclosing envelope for the board and the garments draped thereover comprising two complementary side members in the form of flexible sheets, each slightly larger than the board and permanently connected along at least one edge, closure means to connect the other edges of the side members, and a handle to carry the luggage with the garment supporting edge of the board uppermost.

4. Hand luggage comprising, a flat rigid supporting member having a garment supporting bar over which garments to be carried may be draped to hang on opposite sides of said supporting member, a garment hanger over which garments to be carried may be draped preparatory

to being applied to said supporting member, means to mount said hanger at a point remote from the garment supporting bar to facilitate the arrangement of garments on the supporting member, said supporting member being of a size to extend beyond the sides and beneath the bottom of garments draped over its bar, and a flexible enclosing envelope for the supporting member comprising two complementary side members in the form of sheets of flexible material each 10 slightly larger than the supporting member and connected to each other along one edge, and closure means to readily detachably connect the side members along their other edges.

5. Hand luggage of the character described, 15 comprising a substantially flat enclosing envelope consisting of two complementary side members formed of flexible material and permanently connected along at least one edge, interlocking fastening means extending along the 20 other edges of the side members for quickly detachably connecting the same, and garment supporting means within the enclosing envelope comprising a flat rigid support smaller than the side members and having a garment supporting 25 bar at one edge over which garments to be carried are draped to hang on opposite sides of said flat rigid support where they are held by the side members, means to hingedly connect the opposite edge of the flat rigid support to the 30 envelope and a handle to carry the luggage with said garment supporting bar uppermost and the hinged connection between the flat rigid support of the envelope lowermost.

6. Hand luggage of the character described, 35 comprising a relatively flat flexible enclosing envelope, consisting of two complementary side members in the form of sheets of flexible material permanently and hingedly connected along at least one edge, interlocking fastening means 40 extending along the other edges of the side members for quickly detachably connecting the same, a stiff garment supporting board smaller than the side members, means to hingedly connect one edge of the garment supporting board to the 45 enclosing envelope near one edge of the envelope when closed so that it forms a rigid and stiff support for the envelope, means on said garment supporting board to hold said garments in neatly folded arrangement draped over another edge 50 of the board to hang on opposite sides of the board where they are held by the side members, and a handle to carry the luggage with said second designated edge of the board over which 55 the garments are draped uppermost.

7. Hand luggage of the character described, comprising a substantially flat flexible enclosing envelope consisting of two complementary side members in the form of sheets of flexible material connected along at least one edge, interlocking fastening means extending along the other edges of the side members to close the envelope along said edges, and garment supporting means within the enclosing envelope comprising a rigid supporting member of such size 60 that the side members extend beyond the edges of the supporting member to enable expansion of the thickness of the envelope as necessitated by the contents thereof, means hingedly connecting the supporting member to the enclosing envelope so that said supporting member provides a stiff support for the enclosing envelope, and means on a supporting member to support 65 garments in neatly folded arrangement draped over opposite sides of said supporting member 70

to be held against displacement by the side members of the enclosing envelope.

8. Hand luggage of the character described, comprising a substantially flat enclosing envelope consisting of two complementary side members connected along at least one edge, interlocking fastening means extending along the other edges of the side members to close the envelope along said edges, garment supporting means within the enclosing envelope comprising a rigid supporting member providing a stiff support for the enclosing envelope and having means to support garments in neatly folded arrangement draped over opposite sides of said supporting means to be held against displacement by the side members of the enclosing envelope, and a shallow drawer mounted in the garment supporting means and arranged to pull out from the side of the supporting means so as not to disturb garments on the supporting means.

9. Hand luggage of the character described comprising, a flat flexible enclosing envelope consisting of two complementary side members in the form of sheets of flexible material connected along at least one edge, interlocking fastening means extending along the other edges of the side members to close the envelope along said edges, garment supporting means within the enclosing envelope comprising, a flat rigid support having a garment supporting bar at one edge over which garments to be carried are draped to hang on opposite sides of said flat rigid support, a garment hanger over which the garments to be carried are draped preparatory to being engaged on said support, means to readily detachably mount the garment hanger on one side of the flat rigid support at a distance from the supporting bar, and means on the other side of the flat rigid support to hold the adjacent ends of the garments against said support, and means to hingedly connect the edge of the flat rigid support opposite the supporting bar to the enclosing envelope.

10. Hand luggage of the character described comprising, a flat enclosing envelope consisting of two complementary side members connected along at least one edge, interlocking fastening means extending along the other edges of the side

members to close the envelope along said edges, and garment supporting means within said enclosing envelope comprising a flat board smaller than the side members and having a garment supporting bar at one edge over which garments to be carried are draped to hang on opposite sides of said board, and a flap connected to the board to overlie the ends of the garments on one side thereof and hold the same in place.

11. Hand luggage of the character described comprising, a flat flexible enclosing envelope consisting of two complementary side members in the form of sheets of flexible material connected along one edge, interlocking fastening means extending along the other edges of said side members to close the envelope along said edges, a flat stiff board smaller than the side members and having a garment supporting bar at its upper edge over which garments to be carried may be draped to hang on opposite sides of said board, and means to hingedly connect the lower edge of the flat stiff board to the envelope so that the flat stiff board is permanently attached to the envelope and affords a stiff support therefor.

12. Hand luggage of the character described comprising, a flat flexible enclosing envelope consisting of two complementary side members connected along their bottom edges, interlocking fastening means extending along the other edges of the side members to close the envelope along said edges, and garment supporting means within said enclosing envelope comprising a flat stiff board having a garment supporting bar at one edge over which garments to be carried may be draped to hang on opposite sides of said board, said board being of a size to extend beyond the sides and beneath the lower edges of the garments draped thereon, and being smaller than the side members, a permanent hinged connection between the edge of the board opposite its garment supporting bar and the lower closed edge portion of the enclosing envelope whereby the board is permanently connected with the enclosing envelope in a position at which its garment supporting bar is located adjacent the upper edge of the envelope, and handle means at the upper edge portion of the envelope.

GEORGE HENRY WHEARY.
